US00D890811S

(12) United States Design Patent (10) Patent No.: US D890,811 S
(45) Date of Patent:  *Jul. 21, 2020

(54) DISPLAY SCREEN WITH GRAPHICAL USER INTERFACE

(71) Applicant: Google LLC, Mountain View, CA (US)

(72) Inventors: Rachel Inman, San Francisco, CA (US); Jeremy Edelblut, Sunnyvale, CA (US); Marek Gorecki, Los Gatos, CA (US); Joost Korngold, Sunnyvale, CA (US)

(73) Assignee: GOOGLE LLC, Mountain View, CA (US)

(*) Notice: This patent is subject to a terminal disclaimer.

() Term: 15 Years

(21) Appl. No.: 29/703,016

(22) Filed: Aug. 23, 2019

Related U.S. Application Data

(63) Continuation of application No. 29/646,664, filed on May 7, 2018.

CLAIM

The ornamental design for a display screen with graphical user interface, as shown and described.

DESCRIPTION

The sole FIGURE is a front view of a display screen with graphical user interface, showing the new design.

The broken lines of uneven length show the display screen and form no part of the claimed design.

1 Claim, 1 Drawing Sheet
